(57) **CLAIM**

The ornamental design for a charger for smart watch, as shown and described.

DESCRIPTION

1. Charger for smart watch

1.1 : Front

1.2 : Back

1.3 : Left

1.4 : Right

1.5 : Top

1.6 : Bottom

1.7 : Perspective

1.8 : Perspective

1.9 is a perspective view of the charger for smart watch shown in an environment.

In reproduction 1.9 the broken lines are for the purpose of illustrating environment only and form no part of the claimed design.

1 Claim, 9 Drawing Sheets
